UNITED STATES PATENT OFFICE

2,019,679

CENTRIFUGAL PUMP

Oystein Jacobsen, Dayton, Ohio, assignor to The Duriron Company, Inc., a corporation of New York

Application July 12, 1935, Serial No. 30,997

5 Claims. (Cl. 103—103)

The invention relates to centrifugal pumps, and more particularly to those in which the materials employed in the pump body are of corrosion resisting material, such as high silicon iron which is relatively brittle and frangible. The principal object of the invention is the provision of a construction in which the casing part carrying the volute is placed under compression, thus eliminating any danger of breakage incident to the pressure developed in the volute and resulting from the operation of the pump. One embodiment of the invention is illustrated in the accompanying drawings, wherein:

Figure 1 is a vertical section through the pump. Fig. 2 is an elevation of one side of the pump. And Fig. 3 is a partial elevation of the other side of the pump.

Referring to the drawings, 1 and 2 are parts of the pump casing, the part 1 being provided with the volute 3, and the part 2 having the inlet connection 4 leading to the eye of the pump. Mounted in the casing is the runner or impeller 5 having the usual radial passages 6 discharging to the volute, the runner being driven by the shaft 7 which carries at its other end a pulley (not shown) or other suitable driving means. The volute discharges at 8 into the outlet passage 9 which is connected with the usual discharge pipe (not shown).

The base casting 10 of the pump is provided at its right hand end with a base plate 11 integral with such casting and having at its edge the flange 12 which fits around a ring or flange 13 carried by the part 1 of the pump casing. The base plate 11 is provided with the vertical slot 14 which may be from one-eighth to one-quarter inch in width, and extends down to the circular opening through which the stuffing box and shaft project. Provision is made for clamping the base plate onto the ring 13 by the use of the bolt 15. When the bolt is tightened, the spring in the base plate, incident to the use of the slot 14, permits the flange 12 to apply compressive force on the ring 13, so that the casing part 1 carrying the volute is reinforced against breaking strain incident to pressure generated in the volute by the operation of the impeller. The link 16 carried by the bolt 15 is used for lifting and handling purposes.

The pump casing part 1 carrying the volute is placed under compression in a direction axially of the pump and the casing parts 1 and 2 and clamped in assembled relation by means of the set of bolts 17, 17, 17, etc. extending through the flange of the base plate 11 and a clamping ring

18, which engages the face of the part 2. The casing part 1 carrying the volute is thus placed under compression in two directions by the action of the bolts 15 and 17, 17, 17, etc. and danger of fracture incident to pressure generated in the volute is reduced to a minimum, even in those cases in which the alloy of which the casing parts are formed is relatively weak and brittle. The danger of breaking the pump in handling is also reduced to a minimum by the expedient as above set forth.

What I claim is:

1. In combination in a centrifugal pump, a casing having an inlet eye at its center and a volute around its periphery, a runner mounted in the casing provided with a drive shaft, a ring rigid with the casing projecting laterally from one side thereof adjacent the periphery of the casing and the volute, a supporting base for the pump provided with a slotted base plate having a flange fitting around said ring, and clamping means for partially closing the slot in the base plate to cause the flange thereof to apply compressive force upon said ring and to the entire side wall of the casing inward of the volute.

2. In combination in a centrifugal pump, a casing having an inlet eye at its center and a volute around its periphery, a runner mounted in the casing provided with a drive shaft, a ring rigid with the casing projecting laterally from one side thereof adjacent the periphery of the casing and the volute, a supporting base for the pump provided with a slotted base plate having a flange fitting around said ring, and a clamping bolt extending transversely of the slot in the base plate and adapted to partially close said slot to cause the flange thereof to apply compressive force upon said ring.

3. In combination in a centrifugal pump, a casing comprising a part having a volute around the outer portion, and a cover plate provided at its center with an inlet, a runner mounted in the casing provided with a drive shaft, a ring rigid with the casing part projecting laterally from one side thereof adjacent the periphery of the casing and said volute, a supporting base for the pump provided with a slotted base plate having a flange fitting around said ring, clamping means for partially closing the slot in the base plate to cause the flange thereof to apply compressive force upon said ring, a clamping ring engaging the outer face of the cover plate, and bolts extending from the periphery of the clamping plate to the flange of the base plate outside the periphery of the casing for applying compressive force to the

- casing in a lateral direction and clamping the casing parts in assembled relation.
4. In combination in a centrifugal pump, a casing having an inlet eye at its center and a volute around its periphery, a runner mounted in the casing provided with a drive shaft, a ring rigid with the casing projecting laterally from one side thereof adjacent the periphery of the casing and the volute, a supporting base for the pump provided with a slotted base plate having a flange fitting around said ring, a clamping bolt extending transversely of the slot in the base plate and adapted to partially close said slot to cause the flange thereof to apply compressive force upon said ring, and a set of clamping bolts in parallel with the axis of the pump for clamping the base plate to the casing.
5. In combination in a centrifugal pump, a

casing having an inlet eye at its center and a volute around its periphery, a runner mounted in the casing provided with a drive shaft, a ring rigid with the casing projecting laterally from one side thereof adjacent the periphery of the casing and the volute, a supporting base for the pump provided with a slotted base plate having a flange fitting around said ring, a clamping bolt extending transversely of the slot in the base plate and adapted to partially close said slot to cause the flange thereof to apply compressive force upon said ring, a handling link on said bolt, and a set of clamping bolts in parallel with the axis of the pump for clamping the base plate to the casing and for applying compressive force to the casing in a lateral direction.

O. JACOBSEN.
